SUCTION TONSILLECTOME

Roderick Franklin Brown, Altus, Okla.

Application April 9, 1934, Serial No. 719,778

4 Claims. (Cl. 128—309)

My invention relates to new and useful improvements in suction tonsillectomes and has for its primary object to provide an effective device which will enable a surgeon to enucleate a patient's tonsils safely and with as little inconvenience as possible to the patient and to the surgeon.

Another object of my invention is to provide a simple, small and practical instrument which is so constructed that it may be operated entirely by one hand, thereby leaving the operator's other hand free to assist him in doing other necessary things.

A further object is to provide an instrument which may be used by either a right-hand or a left-hand operator.

A further object is to provide an instrument of the kind specified which combines in one compact structure the tonsil snare mechanism and a suction mechanism for holding the tonsil in the instrument while the tonsil is being removed; also to provide the instrument with a swivel thumb eye and with a suction controlling valve that can be operated by the thumb while the thumb is in the eye and while the index and second fingers of the hand are being used to operate the snare.

Other objects will in part be obvious and in part be pointed out hereinafter.

To the attainment of the aforesaid objects and ends the invention still further resides in the novel details of construction, combination and arrangement of parts, all of which will be first fully described in the following detailed description and then be particularly pointed out in the appended claims, reference being had to the accompanying drawings, in which:—

Figure 1 is a top plan view of my invention.

Figure 2 is a bottom plan view of my invention.

Figure 3 is a side elevation thereof.

Figure 4 is a central vertical longitudinal section thereof.

Figure 5 is an enlarged detail plan view of the cup end of the invention with the cup removed.

Figure 6 is an enlarged side elevation of the cup.

Figure 7 is an enlarged bottom plan view of the cup.

Figure 8 is an enlarged cross section on line 8—8 of Figure 3.

Figure 9 is a horizontal section on line 9—9 of Figure 8.

Figure 10 is an enlarged perspective view of the cross head with the finger holes.

Figure 11 is a detailed perspective view of a portion of the snare-operating rod.

Figure 12 is a cross section on line 12—12 of Figure 4.

Figure 13 is a cross section on line 13—13 of Figure 4.

Figure 14 is an enlarged longitudinal section of 5 the air-valve.

Figure 15 is a cross section on the line 15—15 of Figure 3.

In the drawings in which like numerals of reference indicate like parts in all of the figures, 1 is an 10 elongated cannula body having a tonsil-receiving loop 2 at one end which is provided with a snare-receiving groove 3. The body 1 is bored at 4 for the reception of the snare-operating rod 12, the bore extending from the loop 2 to a transverse 15 slot 5 in the body 1. A sliding block or cross head 6 operates in the slot 5 and projects to either side of the body 1 where it is provided with finger holes 7. The block 6 is dove-tailed at 8 so as to fit the body 1 and prevent lateral displacement 20 of the block. As will appear most clearly in Figure 11, the block 6 has a recess 9 to receive the head 11 and a recess 10 to receive the adjacent portion of the rod 12.

At its front end the rod 12 has grooves 13 in 25 its side and cross holes 14 to receive the ends of the snare 15, the snare 15 being a flexible, resilient, fine wire.

The loop 2 has a recess 16 to receive the flange 18 of the cup 17, the cup being composed of glass 30 or other suitable transparent material. It is formed with a suction nozzle 19 whose passage 20 registers with the port 22 at the forward end of the suction duct 21 that passes longitudinally through the body 1 to adjacent its rear end. At 35 the rear end of the duct 21 the body is provided with a bore 23 for the valve 25 which controls the suction in the duct 21. The body 1 at the bore 23 is provided with a nipple 24 to which a suction line from a suitable vacuum pump, or 40 other suction source, may be connected. The valve 25 has a port 31 to effect communication with the duct 21 when the valve is pressed in against the tension of the spring 30 that is housed in the collar 28 which is welded, or otherwise secured, to the body 1. The movement of the valve 45 is limited by a pin 27 and slot 26 connection.

32 is the coupling member which, as will best appear from Figures 3 and 4, is provided with recesses 33 to receive the end of the body 1 to 50 which it is secured by a screw 34. The coupling 32 has a swivel stub 35 that is riveted over in the swivel bearing 37 of the thumb eye 36. The cup 17 is held in place by cement or other suitable means.

From the foregoing it will be seen that to use the instrument the thumb is thrust through the loop or eye 36 so that the ball of the thumb rests well over the head 29 of the valve 25. The index and second fingers are placed in the loops 7 respectively of the sliding block 6 and by pulling with the fingers in the loops 7 the block 6 will slide toward the thumb eye 36, pulling the rod 12 backward and drawing the snare 15 into the small hole occupied by the rod 12. It should, of course, be understood that before the snare is drawn in the instrument is placed over the tonsil and the valve 25 is moved to cause suction to draw the tonsil well into the cup 17. Pulling back the rod 12 as above described produces a strangulation or cutting effect upon the tonsil which is surrounded by the snare. As soon as the snare has been drawn in and the tonsil severed the instrument may be removed from the patient's throat and mouth and, by allowing the valve 25 to close, the suction is cut off and the severed tonsil may be removed from the cup.

As the entrance to the port or duct 20 is located at the upper portion of the cup the suction tends to draw in a direction along the axis of the tonsil rather than in a lateral direction, as would be the case if the port were at the base of the cup. This action pulls the tonsil well into the cup and the inside contour of the cup is such that once the tonsil is inside it will be somewhat gripped in the small opening to the port 20 and held securely in the cup.

The instrument may be used with either the right hand or the left hand as the surgeon may desire. It should also be understood that the rod 12 is made to fit the bore 4 air-tight so that sufficient suction can be established in the cup 17 and the loop 2 at the beginning of the operation to insure the tonsil being drawn up into the cup.

From the foregoing description, taken in connection with the accompanying drawings, it is thought that the complete construction, arrangement, operation and advantages of my invention will be clear to those skilled in the art to which it appertains.

What I claim is:

1. A tonsillectome comprising an elongated body having at one end a tonsil-passing loop, 50 a cup held on said loop to receive the tonsil, means operable in said body for severing the tonsil, said body and cup containing a suction duct, a suction valve in said body to control said duct, and a thumb-engaging member at the other end of said body, said means including an oper-

ating member having finger-engaging portions, said operating member, said valve and said thumb-engaging member being located in positions permitting simultaneous operation in virtue of which the instrument may be operated by 5 one hand.

2. A tonsillectome comprising an elongated body having at one end a tonsil-passing loop and at the other end a swivel thumb eye, said body having a transverse slot, a cross-head 10 mounted on said slot and having finger openings, said body having a bore extending from said slot to said loop, a rod in said bore, and having a connection to said cross-head, an end of said rod being projectable into said loop, a 15 snare in said loop and connected to said end of said rod, a tonsil-receiving cup mounted on said loop, said cup and said body containing a suction duct, a suction valve carried by said body to control passage through said suction duct, 20 said cross-head, said valve and said eye being located in cooperative position for actuation by one hand.

3. A tonsillectome comprising an elongated body having at one end a tonsil-passing loop and at the other end a swivel thumb eye, said body having a transverse slot, a cross-head 25 mounted on said slot and having finger openings, said body having a bore extending from said slot to said loop, a rod in said bore, and having a connection to said cross-head, an end of said rod being projectable into said loop, a 30 snare in said loop and connected to said end of said rod, a tonsil-receiving cup mounted on said loop, said cup and said body containing a suction duct, a suction valve carried by said body to control passage through said suction duct, said connection comprising a head on said rod and a recess in said cross-head to receive said rod-head and the adjacent portion of said rod. 40

4. A tonsillectome comprising an elongated body having at one end a tonsil-passing loop, a cup held on said loop to receive the tonsil, means operable in said body for severing the tonsil, said body and cup containing a suction 45 duct, a suction valve in said body to control said duct, and a thumb-engaging member at the other end of said body, said means including an operating member having finger-engaging portions, the entrance to said suction duct within the cup 50 being located at the crown of the cup in virtue of which the suction tends to draw in a direction along the axis of the tonsil.
